CLAIM

The ornamental design for a dosing bottle, as shown and described.

DESCRIPTION

FIG. 1 is a perspective view of a dosing bottle; FIG. 2 is a left side view of the dosing bottle of FIG. 1; FIG. 3 is a right side view of the dosing bottle of FIG. 1; FIG. 4 is a front view of the dosing bottle of FIG. 1; FIG. 5 is a rear view of the dosing bottle of FIG. 1; FIG. 6 is a top view of the dosing bottle of FIG. 1; and, FIG. 7 is a bottom view of the dosing bottle of FIG. 1. The broken lines in FIG. 7 depict portions of the dosing bottle that do not form part of the claimed design.

1 Claim, 6 Drawing Sheets
